(57) **CLAIM**

The ornamental design for a lighter as shown and described.

DESCRIPTION

FIG. 1 is a perspective top front view of the lighter showing our new design;

FIG. 2 is a perspective bottom back view thereof;

FIG. 3 is a front view thereof;

FIG. 4 is a back view thereof;

FIG. 5 is a left side view thereof;

FIG. 6 is a right-side view thereof;

FIG. 7 is a top view thereof;

FIG. 8 is a bottom view thereof;

FIG. 9 is a perspective top front view of the lighter in open configuration;

FIG. 10 is a perspective bottom back view in open configuration thereof;

FIG. 11 is a front view in open configuration thereof;

FIG. 12 is a back view in open configuration thereof;

FIG. 13 is a left side view in open configuration thereof;

FIG. 14 is a right side view in open configuration thereof;

FIG. 15 is a top view in open configuration thereof; and,

FIG. 16 is a bottom view in open configuration thereof.

The broken lines illustrate portions of the lighter that form no part of the claimed design.
